CASTING APPARATUS AND METHOD

Application filed January 27, 1932. Serial No. 589,068.

This invention as indicated relates to a casting apparatus and method. More particularly it relates to the production of castings in permanent or semi-permanent molds, and especially with metals having a low melting point and high crystallization shrinkage.

Heretofore it has been the practice in casting various objects, particularly those having thin walls, from metals having a low metal point and high crystallization shrinkage, to adopt either the method of supplying adjacent one edge of the casting a considerable body of molten metal serving as a reservoir to be drawn upon by the metal within the casting cavity in the course of its solidification and to supply the extra metal needed through shrinking, such shrinking being caused to take effect initially at a point remote from the position of such excess supply of molten metal, as is clearly described in the patent to Norton, No. 1,296,595, or the casting of a thin-walled section has been carried out by supplying to the base of the mold through a gate communicating with the periphery thereof substantially throughout its entire extent, practically all of the metal for the entire casting, such metal flowing in a wide substantially continuous web through a circumferential gate supplied from a peripheral runner and thence proceeding rapidly toward the upper portion of the casting, the entire casting being thus supplied from the base to provide a smooth surface finish above the periphery of the base, the entire mass of the casting then solidifying substantially at one time, as is set forth in the patent to Fahlman, No. 1,770,386.

The present invention has in view the production of thin-walled castings wherein the metal supply for the body portion thereof is not derived solely from ingates adjacent the peripheral portions of the base, nor is supplied in successive horizontal layers from a large reservoir of molten metal, so that shrinkage losses may be made up by drawing upon such reservoir of metal in the course of progressive solidification of the article, but is carried out by supplying the metal to the casting cavity at a plurality of points simultaneously and admitting the metal to the

casting cavity through gates of narrow width having the effect of flowing such metal into the interior of the cavity as a smooth non-turbulent stream, and diverting oxides and impurities from such gates through the angularity of the passageways leading thereto. It also has in view the provision of a method of manufacturing castings from aluminum and aluminum alloys and the like, wherein the casting cavity is supplied through gates of unusual thinness, which serve substantially as valves between the molten metal supply and the metal admitted to the casting cavity, such gates having so little mass that the metal therein freezes substantially instantaneously upon the cessation of flow of molten metal therethrough; and because of the slight mass of the gates has no appreciable effect in causing draws which would distort or affect the even contour of the casting or permit interference therewith through the excess of metal in the molten metal supply on the opposite side of such gates. Thus, after the closing of the gates through the freezing of the same, the metal within the casting cavity beneath the level of such gates will begin to solidify and, having so little mass of metal to draw upon in the gate, will be unaffected by the gate and will shrink uniformly throughout such portion of the molding cavity because of there being no body of molten metal adjacent to such freezing mass which could be drawn upon to supply the shrinkage losses. The shrinkage undergone by a casting in the manner stated will thus be uniform throughout and any difference in size of the product will be adequately taken care of through the allowance for such shrinkage in the original design of the molds.

In addition to facilitating the production of castings through the use of permanent or semi-permanent molds, the use of gates of extreme thinness provides for the economical removal of the waste material from the casting proper after the same is taken from the mold. It has been found that gates having a thinness of approximately $\frac{1}{2}$ of an inch when the objects are formed of aluminum or aluminum alloys are readily frangible and by sharply tapping the mass of runners and

sprues about the margins of the casting, the same will be freed at once from the body of the casting through the fracturing of the gates close to the margins of the casting. 5 This obviates the necessity of any sawing operations on the casting and in cases where trimmed edges are required, permits the immediate positioning of the casting in an automatic lathe for such finishing operations as 10 are required.

10 The invention permits the direct feeding of metal through thin-walled sections such as the wing members of castings for agitators for washing machines without in any way interfering with the smooth contour of the finished article, even though in current practice it has been considered improper to supply metal to a casting through such thin-walled extensions upon the theory that the 15 flow of hot metal over such walls would heat the same to too great an extent and cause uneven cooling together with all of the imperfections and irregularities which are consequent thereon. Thus, with the method and 20 apparatus herein set forth, it is possible to rapidly supply metal to a casting cavity through a large number of gates distributed at a wide variety of points about a casting and it is also possible to feed directly into 25 a thin-walled section such as a fin or wing of an agitator for washing machines without in any way causing any imperfections in the casting either as to the body of such casting or as to such thin-walled extensions or 30 wing portions thereof.

35 In addition to the advantages pointed out above, there are many other advantages which are to be found in the invention herein set forth as will appear in the course of the following description.

40 To the accomplishment of the foregoing and related ends, said invention, then, consists of the means and steps hereinafter fully described and particularly pointed out in the 45 claims. The annexed drawings and the following description set forth in detail certain structures embodying such invention, and the method of making the same, such disclosed means and method constituting, however, but 50 several of various applications of the principle of my invention.

In said annexed drawings:

55 Figure 1 is a vertical sectional view of the apparatus taken along the line 1—1, shown in Figure 2, looking in the direction of the arrows;

Figure 2 is a top plan view, partly in section, taken along the line 2—2, shown in Figure 1, looking in the direction of the arrows;

60 Figure 3 is a side elevation of a casting formed in the apparatus illustrated in Figures 1 and 2;

Figure 4 is a top plan view, partly in section, taken along the line 4—4, shown in Figure 3, looking in the direction of the arrows;

Figure 5 is a top plan view, partly in section, of the casting shown in Figure 3, taken along the line 5—5, shown in Figure 3;

Figure 6 is a horizontal sectional view taken through the stem portion of the casting adjacent the plane indicated by the line 5—5, shown in Figure 3, and showing the details of the vertical gate;

Figure 7 is a greatly enlarged sectional view of the gate and adjacent structure shown in Figure 6;

Figure 8 is a view similar to Figure 1, illustrating a modified form of casting apparatus, the section being taken along the line 8—8, shown in Figure 9, looking in the direction of the arrows;

Figure 9 is a plan view, partly in section, taken along the line 9—9, shown in Figure 8, looking in the direction of the arrows;

Figure 10 is a side elevation of a casting formed in the apparatus shown in Figures 8 and 9;

Figure 11 is a sectional plan view taken along the line 11—11, shown in Figure 10, looking in the direction of the arrows;

Figure 12 is a top plan view, partly in section, taken along the line 12—12, shown in Figure 10, looking in the direction of the arrows;

Figure 13 is a sectional view, taken along the line 13—13, shown in Figure 10, looking in the direction of the arrows; and

Figure 14 is a fragmentary sectional view corresponding to a portion of the illustration of the casting cavity shown in Figure 8, but showing a modified form of vertical sprue and passageways associated therewith.

As is clearly shown in Figures 1 and 2 of the drawings, the apparatus comprises a base 1 in the form of a heavy annular metal member supported upon a frame 2 preferably having a series of legs and cross members, said base having a central opening preferably of circular outline through which a movable core section 3 is engaged, said core section being held against rotation by a key 3a engaging in a keyway 3b, and having adjacent its lower edge a projecting flange 4 adapted to limit the upward motion thereof and having an upper surface presenting a substantially flat area 5 merging with a tapered stem section 6. The core is preferably supported upon a standard 7 screw-threadedly engaged therewith and formed adjacent its lower end with a rack 8 adapted to be engaged by a pinion 9 the shaft of which when operated by a handle bar 10 will reciprocate the core section, drawing the same downwardly into the base upon the completion of the casting.

On the upper face of the base member a plurality of pivoted mold sections is provided, each mold section having a body portion adapted to overlie the margins of the base member and the adjacent core surface, and having side plates adapted when in op-

erative position to meet corresponding side plates on companion mold sections.

The apparatus illustrated shows three movable mold sections, 11, 12, 13, each centrally supported upon a hinge member 14 and adapted to be moved outwardly from its operative casting position to an inclined position with reference to the base to a distance sufficient to permit the free removal of the finished casting. A boss adjacent the lower section of each mold section is provided with a vertical socket within which a bar or lever 15 is engaged to move the mold section into and out of operative position. A horizontal socket is also provided in the boss in which a handle 16 may be secured, such handle being preferably of a length sufficient to serve as a support or prop for its mold section when in open position. The inner face of each movable mold section is recessed adjacent the core surface to provide a casting cavity for the body portion of the article to be formed, and blocks 20 bring said sections into accurate registry.

In the apparatus illustrated, an agitator for a washing machine is indicated as the product and such articles have a series of wings, in this instance, three radially spaced wing members 17, 18, 19, being shown, and the adjacent faces of the movable mold section are each recessed to provide a casting cavity continuous with the casting cavity for the body portion of the article referred to, so that integral wings may be formed when metal is supplied to such mold in its operative position.

The core member, as heretofore stated, is formed with an upwardly extending stem section which may be formed of metal throughout or, as shown in Figures 1 and 2 of the drawings, may be of metal as to its lower section and with a composition core 21 for the upper section of the stem. In order to satisfactorily position the composition core above the permanent stem section of the core, the latter is formed with a small squared extension, 22 on its upper surface over which the composition core may be engaged and held against radial displacement. The composition core preferably is formed with a supporting wire 23 embedded centrally therein and projecting above the same and adapted to be supported at its upper end 24 by means of the frictional clamping action of the upper beveled portion 25 of the assembled mold sections immediately above the stem. A riser cavity 30 is formed immediately above the composition core, and the supporting wire extends therethrough.

In order to supply metal to the casting cavity above described, the meeting faces along two of the parting lines of the mold sections are recessed to provide a vertical sprue cavity 26 which preferably extends downwardly and outwardly for convenience of arrange-

ment and economy of space, as shown in Figure 1, the lower end being somewhat reduced in width and outwardly offset from the main body portion thereof and entering an arc-shaped runner cavity 27 formed in the adjacent faces in the base and movable mold sections and provided at spaced intervals with thin horizontal gates 28, preferably about $\frac{1}{2}$ of an inch in thickness, feeding into the adjacent portion of the base of the casting cavity. Said meeting faces of the respective movable molds are also each recessed to provide a vertical wing feed runner 29 spaced from the outer margin of the casting cavity for the adjacent wing section, such runner at its lower end merging with the peripheral runner cavity 27 and having preferably one or more cross-feeder passageways 31, 32, above the same, in the present case two being indicated, one 31 at a point opposite the angle of the wing and another 32 approximately midway of the upper portion of the stem portion of the casting cavity. The runner referred to may also extend upwardly a slight distance beyond the top of the wing section in the form of a riser.

In order to supply metal from the wing feeder runner to the adjacent wing, vertical gates 33, 34, of small thickness, preferably of about $\frac{1}{2}$ of an inch may be provided, the gates preferably being formed adjacent the lower vertical edge of the wing cavity and adjacent the vertical portion of the upper wing section of the casting cavity. In order to supply metal to the wing 19, formed at the parting plane of the mold faces not recessed for a pour-sprue, an extension, 35, is provided on one of the adjacent runners which is opposite such parting plane and communicates at such point with a short vertical riser, 36, of a height substantially equal to that of the adjacent wing and formed with a vertical gate, 37, at an intermediate portion communicating with said wing. Said gate 37 is also made relatively thin, being preferably not over $\frac{1}{2}$ of an inch in thickness.

The casting formed in the apparatus just described, together with its associated sprues and runners, is illustrated in Figures 4 to 6 inclusive, wherein the body portion, 41, of the casting is shown as an inverted trumpet shaped portion having an elongated central stem section, 42, with which three equally spaced wing extensions merge, said wing extensions each having a lower portion, 43, extending substantially to the periphery of the body section and of relatively small height and having an elongated tapered upper portion, 44, merging with the upper section of the stem from a point approximately midway of the lower portion of the wing. The horizontal runners, 45, as indicated, are positioned outwardly of the periphery of the casting and one of said runners is formed

with an extension, 46, for carrying metal to a point opposite the third parting plane, at which point a vertical riser 47 is provided spaced slightly outwardly of the margin of the adjacent wing section with which it communicates by means of a narrow gate portion 48, the riser extending somewhat above the upper end of the gate. The riser may be carried upwardly spaced from the margin of the adjacent wing if the size and character of the casting so requires.

As is clearly shown in Figures 4 and 5, the horizontal gates from the horizontal runners are provided adjacent the ends of such runners but slightly spaced therefrom with narrow gate sections, such gates preferably being of about $\frac{1}{2}$ of an inch in height and extending in the form shown only a small portion of the total extent of the circumferential portion of the mold.

The form of mold just described is intended to produce an agitator for a washing machine wherein three wings equally spaced about the upper surface are provided, as has heretofore been stated.

In the form of construction illustrated in Figures 8 to 13 inclusive, an agitator casting of somewhat different form is shown, such casting having a substantially rectangular outline and being formed with four wings of less height and greater width than the agitator casting first described.

The supporting and operative parts of the structure are substantially the same as those shown in Figures 1 and 2, and the same reference characters have been applied thereto, in so far as they relate to the identical structure. The movable mold sections, 51, 52, 53, 54, in the modified form of construction, are four in number and the core portion 55 of the device is a permanent metal core throughout, no composition extension being employed as in the construction heretofore described. The core member 55 held against rotation by a key 55a engaging in a keyway 55b, and on its upper surface is provided with a marginal area 56 lying substantially in a horizontal plane and adjacent its central portion is curved upwardly toward a stem section 57 tapering slightly in an upward direction. The stem section is a solid cylindrical member having a body portion tapering slightly in an upward direction as stated, and is specially shaped adjacent its upper end 58 to form a shoulder and a rectangular socket within the stem of the casting to provide suitable driving engagement for the agitator. The stem section of the core is secured to the base section of the core through the seating of the base of the stem section within a recess 59, formed centrally of the upper surface of the base section and of a slightly larger diameter than the diameter of the lower portion of the stem in order to form an annular recess on the upper surface of the

combined core members to form a depending flange on the under side of the agitator casting in alignment with the stem section thereof. The stem section of the core is provided with a shoulder and a reduced lower end portion 61 beyond the same adapted to project through a central aperture in the lower section of the core, and to be secured against the same by means of a nut 62 engaged over a screw threaded terminal portion of such reduced section.

The mold is supplied with four movable sections supported on the base by suitable hinge members 63 which sections are each provided with recesses on their inner faces adjacent to the core members to form the body portion of the agitator casting, and are provided on each of their meeting faces along the parting lines of said respective sections with recesses to form the wing portions 64 of the agitator casting. The vertical feeding sprues 65 are formed in the parting planes intermediate the flanges on two of the movable mold sections on one side of the apparatus, and like recesses in the directly opposite pair of mold sections along the parting plane in alignment with the first mentioned parting plane. The two parting planes between the respective mold sections at right angles with the parting planes just referred to are not provided with passageways for feeding sprues for the casting here illustrated inasmuch as adequate metal can be supplied to said casting without additional feeding sprues and the labor of filling and operating the mold is considerably reduced by reducing the number of feeding sprues and associated passageways. At the base of the feeding sprues lateral runners 66 of V shaped formation are provided at diagonally opposite corners of the casting cavity, such runners being formed by recesses provided partially in the base of the apparatus and partially in the adjacent under faces of the movable mold sections. The V-shaped sprues are of considerable width and the vertical feeder sprues 65 communicate therewith adjacent the outer edges thereof. A runner 67, spaced slightly from the outer margin of each adjacent wing cavity between the mold faces in which the feeder sprues are located, is provided, and extends from the inner edge of the V-shaped runner in an inwardly curved direction, the upper end thereof 68 extending beyond the position of the upper edge of the wing to provide a riser cavity at such point. A thin gate 69 preferably of not over $\frac{1}{2}$ of an inch in width connects the runner last referred to to the upwardly extending margin of the wing cavity. A cross feeder connection 71 is provided between the feeder sprue and the upwardly extending runner at a point slightly below the lower end of the gate just referred to. The V-shaped runners communicate with

the casting cavity adjacent their respective ends through gates 72 of narrow width and of preferably not more than $\frac{1}{2}$ of an inch in thickness which enter the side portions of the body of the casting cavity adjacent the lower edge thereof at an approximately central position intermediate the wings. A riser cavity 73 is provided immediately above the top of the stem section of the core to receive excessive metal rising through the casting cavity as the filling of the mold nears completion.

A still further modified form of construction is illustrated in Figure 14, wherein the feeder sprue 81 for the mold cavity in place of connecting with the V-shaped runner 82 at its outer edge and having a riser or runner extending upwardly from the inner edge of such V-shaped runner extends directly downwardly into the central portion of the V-shaped runner, and is connected with the adjacent casting cavity for the wing by means of two gates, one 83 entering the vertical end portion of the wing directly from the lower portion of the vertical feeder sprue, and the other 84 entering the curved intermediate portion of the upper edge of the wing through a riser passageway 85 and connected with the feeder sprue at a point slightly above the top of the outer vertical edge of the wing. Each of the gates shown in Figure 14 is formed exactly similarly to the gates preferably used throughout the apparatus which as stated in a thin casting of the type described are preferably made of $\frac{1}{2}$ of an inch in thickness so as to present a very small mass relatively to the adjacent metal in the wing cavity on one side when the mold is in use and the molten metal in the adjacent passageways to which reference has been made.

The invention as has already been stated includes the supplying of metal to the casting cavity from a plurality of sources simultaneously and preferably also includes in each instance the supplying of such metal through gates of such narrow width as to serve after the manner of shut-off valves to separate the metal which has filled the casting cavity immediately adjacent such gates from the supply of molten metal on the opposite side of said gates when the adjacent portion of the casting cavity has been filled with metal and the flow through such gates has substantially stopped. When this action occurs, as will be very clearly evident from Figure 7, the gate 34 intermediate the adjacent margin of the casting 18 and the adjacent edge of the passageway 29 full of molten metal tends to solidify as soon as the temperature drops through the cessation of metal flow through such thin gate. Because of the small mass of the gate there is substantially no appreciable interchange of metal between the gate and the casting due to crys-

tallization shrinkage at the other edge of the gate; the molten metal at the other side of the gate is effectively prevented from passing through the gate into the casting cavity to supply further hot metal during the shrinkage process.

The action just described obviously takes place at each of the gates throughout the apparatus and the method forming a part of this invention includes the steps of supplying molten metal through a plurality of passageways to the casting cavity through a plurality of thin gates each of which gates is adapted to automatically freeze and effectively seal the casting cavity from interchange of metal with the adjacent molten metal supply in the adjacent passageways, when the level of the molten metal within the casting cavity has reached a point at which metal is no longer taken through the gate or gates at the level supplied by such gates. Thus progressively the solidification or freezing of the casting occurs and the shrinkage of the casting takes place uniformly over its entire extent without being subject to draws or the introduction of strains because of the nearness of molten metal to a mass undergoing shrinkage. In this manner a casting can be produced by feeding the same at a large number of points, and even feeding thin walled sections such as the wings of agitator sections directly from a mass of molten metal and free of any injurious effects either as to quality or appearance because of a flow of metal over the walls of the casting cavity preliminary to the final filling of such cavity with the metal which is to remain therein.

The size of the gate obviously must bear a certain relation to the adjacent masses of metal in the casting cavity and in the feeder passageways so as to bring about the valve action or stopping of the gate at the desired time to produce the results referred to. Where the casting itself is a thin walled member of from $\frac{1}{8}$ to $\frac{1}{2}$ of an inch in thickness, the thickness of the gate should preferably be not more than $\frac{1}{2}$ of an inch, and it has been found that gates of still less thickness have worked satisfactorily in connection with castings of this type.

As has already been stated, the advantages accruing through the control of shrinkage by means of the thin gates are not the only advantages which arise through their use, and the invention includes the use of thin gates irrespective of this function originally stated, inasmuch as thin gates are readily frangible, at least while still hot immediately after removal from the mold. The provision of such thin gates brings about a large saving in the cost of finishing castings.

When castings have gates of appreciable thickness it is usually necessary to separate the same from the finished mold by means of

a sawing or grinding operation preliminary to any further finishing of the casting, and this involves considerable delay and expense in connection with the handling of the casting after it is fabricated in the mold.

5 Other modes of applying the principle of my invention may be employed instead of the one explained, change being made as regards the means and the steps herein disclosed, provided those stated by any one of the following claims or their equivalents be employed or embodied therein.

I therefore particularly point out and distinctly claim as my invention:

15 1. The process of casting metal and alloys comprising introducing the molten metal into the casting cavity by pouring the metal downward under the action of gravity toward the casting cavity, restricting its flow adjacent the bottom of the casting cavity, and directing it into the casting cavity in the form of a thin web, which comprises such a small mass of metal that when the casting cavity has been filled to substantially the level of said web and metal flow therethrough has stopped, it will solidify in advance of the metal in the casting cavity and form a seal between said metal and the molten metal supply adjacent the casting cavity.

30 2. The process of casting articles from metal having a low melting point and high crystallization shrinkage, comprising introducing molten metal into the casting cavity by pouring the metal downwardly under the action of gravity toward the casting cavity and in spaced relation thereto and directing the flow laterally and upwardly and directing the upwardly flowing metal into the casting cavity in the form of an upwardly extending thin web which comprises such a small mass of metal that when the casting cavity has been filled to substantially the level of said web and metal flow therethrough has stopped, it will solidify in advance of the metal in the casting cavity and form a seal between said metal and the molten metal supply adjacent the casting cavity.

35 3. The process of casting articles from metal having a low melting point and high crystallization shrinkage, comprising introducing molten metal into the casting cavity by pouring the metal downwardly under the action of gravity toward the casting cavity and in spaced relation thereto and directing the flow laterally and upwardly at a plurality of circumferentially spaced points and directing the upwardly flowing metal into the casting cavity in the form of upwardly extending thin webs, each of which comprises such a small mass of metal that when the casting cavity has been filled to substantially the level of said web and metal flow therethrough has stopped, it will solidify in advance of the metal in the casting cavity and

form a seal between said metal and the molten metal supply adjacent the casting cavity.

4. The process of casting articles from metal having a low melting point and high crystallization shrinkage, comprising introducing molten metal into the casting cavity by pouring the metal downwardly under the action of gravity toward the casting cavity and in spaced relation thereto and directing the flow laterally and then upwardly and directing the laterally flowing metal and also the upwardly flowing metal into the casting cavity in the form of the plurality of thin webs, each of which comprises such a small mass of metal that when the casting cavity has been filled to substantially the level of said web and metal flow therethrough has stopped, it will solidify in advance of the metal in the casting cavity and form a seal between said metal and the molten metal supply adjacent the casting cavity.

5. The process of casting metal and alloys comprising introducing the molten metal into the casting cavity by pouring the metal downward under the action of gravity toward the casting cavity, restricting its flow adjacent the bottom of the casting cavity, and directing it into the casting cavity in the form of a web extending upwardly from the lower part of the casting cavity which comprises such a small mass of metal that when the casting cavity has been filled to substantially the level of said web and metal flow therethrough at said level progressively has stopped, it will solidify progressively in advance of the metal in the casting cavity and form a seal between said metal and the molten metal supply adjacent the casting cavity.

6. The process of casting metals and alloys comprising introducing the molten metal into the casting cavity by pouring the metal downward under the action of gravity toward the casting cavity, restricting its flow and directing a portion of it to flow laterally adjacent to and along the periphery of the bottom of the casting cavity and another portion upward and adjacent to the casting cavity, directing the laterally flowing metal into the casting cavity in the form of a thin horizontal web and directing the upward flowing metal into the casting cavity in the form of a substantially thin web, the amount of metal in each one of the thin webs being so small that when the casting cavity has been filled to substantially the level of each respective web and the metal flow through such respective web has stopped, said webs will solidify in advance of the metal in the casting cavity and form a seal between it and the molten metal supply of said web adjacent the casting cavity.

7. The process of casting metals and alloys comprising introducing the molten metal into the casting cavity by pouring the metal downward under the action of gravity to-

ward the casting cavity, restricting its flow and directing a portion of it to flow laterally and in opposite directions adjacent to and along the periphery of the bottom of the casting cavity and another portion upward 5 and adjacent to the casting cavity, simultaneously directing the laterally flowing metal into the casting cavity in the form of a plurality of thin horizontal webs, and simultaneously and progressively directing 10 the upward flowing metal into the casting cavity in the form of a series of successive thin vertical webs, the amount of metal in each one of the thin webs being so small that when the casting cavity has been filled to 15 substantially the level of each respective web, and the metal flow through said respective web has stopped, the said webs will solidify in advance of the metal in the casting cavity and form a seal between it and the molten 20 metal supply of said web adjacent the casting cavity.

8. The process of casting metals and alloys comprising introducing the molten metal into the casting cavity by pouring the metal 25 downward under the action of gravity toward the casting cavity, restricting its flow and directing it to flow laterally and thence upward in spaced relation to the casting cavity and directing the upward flowing metal 30 into the casting cavity in the form of a thin web which comprises such a small mass of metal that when the casting cavity has been filled to substantially the level of said web 35 and metal flow therethrough at said level progressively has stopped, it will solidify progressively in advance of the metal in the casting cavity and form a seal between it and the molten metal supply adjacent the 40 casting cavity.

9. The process of casting thin-walled articles having a tapered body portion and wings integrally formed therewith from metal having a low melting point and high crystallization shrinkage, comprising introducing molten metal into the casting cavity by pouring the metal downward under the action of gravity toward the casting cavity, restricting its flow and directing a portion of 45 it to flow laterally and in opposite directions adjacent to and along the periphery of the bottom of the casting cavity and thence upward in spaced relation to the casting cavity opposite each respective wing, and simultaneously directing the laterally flowing metal 50 into the casting cavity in the form of a plurality of thin horizontal webs, and directing the upward flowing metal into the casting cavity at said wings in the form of 55 a thin web which comprises such a small mass of metal that when the casting cavity has been filled to substantially the level of each respective web and metal flow therethrough at said level progressively has 60 stopped, it will solidify progressively in

advance of the metal in the casting cavity and form a seal between it and the molten metal supply adjacent the casting cavity.

10. The process of casting thin-walled articles having a tapered body portion and wings integrally formed therewith from metal having a low melting point and high crystallization shrinkage, comprising introducing molten metal into the casting cavity by pouring the metal downward under the action of gravity toward the casting cavity, restricting its flow, and directing a portion of it to flow laterally and in opposite directions adjacent to and along the periphery of the bottom of the casting cavity and thence upward in spaced relation to the casting cavity opposite each respective wing and simultaneously directing the laterally flowing metal into the casting cavity in the form of a plurality of thin horizontal webs and simultaneously and progressively directing the upward flowing metal into the wing and adjacent base portion of the casting cavity in the form of a plurality of series of successive thin webs, the amount of metal in each one of the webs being so small that when the casting cavity has been filled to substantially the level of each respective web, and the metal flow through said respective web has stopped, the said webs will solidify in 90 advance of the metal in the casting cavity and form a seal between it and the molten metal supply of said web adjacent the casting cavity.

11. A mold comprising a plurality of sections having a casting cavity, a sprue, and a narrow gate having substantially flat parallel walls connecting the sprue with the bottom of the casting cavity, said gate being so narrow that the molten metal therein, when the casting cavity has been filled to substantially the level of the metal of said gate and the metal flow therethrough has stopped, will solidify in advance of that in the casting cavity and form a seal between the metal in 105 the casting cavity and the sprue.

12. A mold comprising a plurality of sections having a casting cavity, a plurality of sprues, and a plurality of narrow gates each having a pair of closely spaced walls connecting each respective sprue at spaced points with the casting cavity, said gates each being so narrow that the molten metal therein, when the casting cavity has been filled to substantially the level of the metal of said 115 gates, will solidify in advance of that in the casting cavity and form a seal between the metal in the casting cavity and the respective sprues.

13. A mold comprising a plurality of sections having a casting cavity, a sprue, a runner adjacent to the bottom of the casting cavity and communicating with the sprue, an upright feeder between the casting cavity and the sprue and communicating directly 125 130

with the runner, a series of narrow horizontal gates each having a pair of closely spaced walls on both sides of the upright feeder and communicating with the casting cavity and the runner, and a series of successive narrow vertical gates each having a pair of closely spaced walls communicating with the casting cavity and the upright feeder, said gates being so narrow that the molten metal therein, when the casting cavity has been filled to substantially the level of the metal of said gates and the metal flow therethrough has stopped, will solidify in advance of that in the casting cavity and form a seal between the metal in the casting cavity and the respective sprues.

14. A casting apparatus comprising a metal mold having a base, a movable core section extending upwardly through the central portion of said base and adapted to be withdrawn downwardly therethrough, a plurality of movable mold members supported on said base about said core section and in spaced relation thereto to provide a casting cavity, cavities provided in adjacent faces of said mold sections to form auxiliary extensions of said casting cavity, sprue cavities in said mold members for supplying metal at spaced points adjacent the casting cavity, vertical gates communicating with marginal portions of the extensions of the casting cavity, and runner cavities connecting with said sprue cavities for carrying metal to said vertical gates, said gates each being of small width and substantial area whereby the metal therein will solidify in advance of the metal at either side of said gates.

15. A casting apparatus comprising a metal mold having a base, a movable core section extending upwardly through the central portion of said base and adapted to be withdrawn downwardly therethrough, a plurality of movable mold members supported on said base about said core section and in spaced relation thereto to provide a casting cavity, cavities provided in adjacent faces of said mold sections to form auxiliary extensions of said casting cavity, sprue cavities in said mold members for supplying metal at spaced points adjacent the casting cavity, horizontal gates communicating with the periphery of the lower portion of the casting cavity, and vertical gates communicating with marginal portions of the extensions of the casting cavity, and runner cavities connecting with said sprue cavities for carrying metal to said horizontal and vertical gates, said gates each being of small width and substantial area whereby the metal therein will solidify in advance of the metal at either side of said gates.

16. A casting apparatus comprising a metal mold having a base, a movable core section extending upwardly through the central portion of said base and adapted to be withdrawn

downwardly therethrough, a plurality of movable mold members supported on said base about said core section and in spaced relation thereto to provide a casting cavity, cavities provided in adjacent faces of said mold sections to form auxiliary extensions of said casting cavity, sprue cavities in said mold members for supplying metal at spaced points adjacent the casting cavity, horizontal gates communicating with the periphery of the lower portion of the casting cavity, vertical gates communicating with marginal portions of the extensions of the casting cavity, riser cavities communicating with the vertical gates, and runner cavities connecting with said sprue and riser cavities for carrying metal to said horizontal and vertical gates, said gates each being of small width and substantial area whereby the metal therein will solidify in advance of the metal at either side of said gates.

Signed by me this 22nd day of January, 1932.
